W. LEE HUNTER, OF SEATTLE, WASHINGTON, ASSIGNOR TO ROY W. HUNTER, UNA HUNTER, AND LUELLA C. HUNTER, ALL OF SEATTLE, WASHINGTON.

CAM-MOVEMENT FOR JIG-POLISHERS.

1,134,047.

Specification of Letters Patent. Patented Mar. 30, 1915.

Application filed April 28, 1914. Serial No. 834,938.

To all whom it may concern:

Be it known that I, W. LEE HUNTER, citizen of the United States, residing at Seattle, in the county of King and State of Washington, have invented a certain new and useful Improvement in Cam-Movements for Jig-Polishers, of which the following is a specification.

My invention relates to improvements in dental jig polishers adapted to be employed by dentists in the operation of polishing and cleaning a person's teeth in the treatment of pyorrhea, and the object of my improvement is to provide a polisher which shall embody simple and efficient mechanical devices for converting rotary motion into reciprocatory motion, and which shall be so constructed that all of the working parts thereof shall be completely inclosed whereby such working parts shall be protected from dirt and dust and be effectively prevented from engaging with exterior objects. I accomplish this object by devices illustrated in the accompanying drawings in which—

Figure 1 is a view in longitudinal section of a dentist's jig polisher embodying my invention; Fig. 2 is a view in side elevation of a detail of the same; Fig. 3 is a view in side elevation of another detail of the same, and Fig. 4 is a view in perspective of another detail of the same.

Referring to the drawings, throughout which like reference numerals indicate like parts, 5 is a tubular casing of a dentist's jig polisher which casing is provided at a point about half way between its two ends with a perforated partition 6 which serves as a bearing for a small shaft 7 that may be connected in any desirable manner with a flexible shaft 8 that is adapted to be rotated by a source of power (not shown) whereby such shaft may be rotated. The shaft 7 is provided on one end with an enlarged cup shaped cylindrical portion 9 that is adapted to fit closely within the casing 5 and to bear against the partition 6, as clearly shown in Fig. 1, and within such cup shaped portion 9 is disposed concentrically therewith the enlarged end 10 of another shaft 11, the end 10 of the shaft 11 being encircled with a cam shaped slot 12 provided in its periphery within which slot is disposed the end of a screw or stud 13 that extends through the wall of the cup shaped portion 9 of the shaft 7 whereby when the shaft 7 is rotated the

stud 13 will be caused to move in the cam slot 12 and by its movement in such slot will cause a reciprocating movement to be imparted to the shaft 11, such shaft 11 being provided with an outwardly projecting stud 14 that is adapted to move in a longitudinal straight slot 15 provided in an end piece 16 thus to prevent the shaft 11 from turning, the stud 14 being short enough to permit the end piece 16 to be screwed into the end of the casing 5 whereby all of the working parts of the device shall be completely inclosed within such casing 5 thus making a neat and compact instrument and one wherein there are no movable parts exposed to the touch of the person using such instrument. When the shaft 7 is rotated it rotates the enlarged portion 9 of such shaft and causes the stud 13 to move in the cam slot 12 which cam slot may be of a required shape to cause a reciprocating motion throughout a desired distance to be transmitted to the shaft 11, such shaft 11 sliding within the end piece 16 while the stud 14 moves within the slot 15 to prevent the shaft 11 from turning.

Obviously, various kinds of tools, not shown, may be attached to the outer end of the shaft 11 in a well known manner.

What I claim is:

In a dental jig polisher of the class described, the combination with a casing of tubular form which is provided in its central portion with a perforated partition that is adapted to serve as a shaft-bearing and further provided on one of its ends with an internal screw-threaded portion, of a shaft-bearing member provided on one of its ends with a longitudinal slot through its wall and with an external screw-thread to adapt it to screw within the internal screw-threaded end portion of said casing; a tool-holding shaft movably disposed to extend through said shaft-bearing member concentrically with said casing and provided on its inner end with a cam slot extending around its periphery and further provided with a stud which projects from its periphery into said longitudinal slot to prevent said shaft from rotating while permitting it to move endwise; a rotatable shaft disposed within said casing and concentrically therewith to extend through said shaft-bearing formed by said perforated partition to project from the other end of said casing, the inner end of said rotatable shaft being provided with an

enlarged cup-shaped portion within which such cup-shaped portion is freely disposed the cam slotted inner end of said first named shaft; a cam stud disposed within the wall 5 of such cup-shaped portion to extend into and engage with the cam slot of the inner end of said first named shaft, whereby the rotation of said rotatable shaft shall cause an endwise movement of said first named

shaft; and means for communicating rotary 10 motion to said rotatable shaft.

In witness whereof, I, hereunto subscribe my name this fifteenth day of April A. D., 1914.

W. LEE HUNTER.
